UNITED STATES PATENT OFFICE

2,198,942

COASTER

Ira S. Leggitt, Oblong, Ill.

Application April 30, 1938, Serial No. 205,366

2 Claims. (Cl. 280—87.01)

This invention relates to improvements in velocipedes, and more particularly to an occupant propelled coaster, which is provided with a pivoted operating lever connected to a suitable train of gears to the rear axle of the coaster.

An object of my invention is to provide an improved coaster which is formed with a pivoted operating lever connected through a train of gears with the rear axle of the coaster, whereby the same may be propelled, together with steering means also connected with the operating lever whereby the coaster may be manually steered.

Another object of my invention is to provide an improved velocipede, which will be manually operated and steered, and which will be provided with gear shift means for selectively changing the gear ratio for operation on the level ground or for operation on hilly ground.

A still further object of my invention is to provide an improved velocipede, of the multiple wheeled, occupant so called type, which may be both steered and propelled by a single pivoted operating lever.

Another object of my invention is to provide an improved velocipede, and more particularly a coaster, in which there is a pivoted operating lever with a handle bar at the upper end, and suitable foot rests adjacent the lower end of said lever, the said lever being connected with and through a train of gears, which in turn are connected with the rear axle, whereby the coaster may be steered and propelled.

A further object of my invention is to provide an improved velocipede, of the coaster type, which will be manually propelled, and which will be highly efficient in operation and quite inexpensive to manufacture.

Other objects will appear as the description proceeds.

In the accompanying drawings which form a part of my application,

Figure 1 is a vertical sectional view through my improved coaster showing the interconnected propelling and steering mechanism therefor;

Figure 2 is a sectional view taken on the line 2—2 of Figure 1;

Figure 3 is a bottom plan view of my improved coaster;

Figure 4 is a sectional view taken on the line 4—4 of Figure 1;

Figure 5 is a sectional view taken on the line 5—5 of Figure 1, and

Figure 6 is a modification of the steering mechanism.

Like characters of reference are used through-

out the following specification and the accompanying drawings to designate corresponding parts.

In carrying out my invention, I provide a velocipede of the self propelled coaster type having a body 1, formed with spaced longitudinally extending slots 2 through which the legs of the occupant will be placed when riding upon the coaster. The body 1 is also provided with the side rails 3 and 4, which extend somewhat above and below the said body, and nearly the full length thereof, and also a connecting plate or back 5, which will be secured to the rear ends of the side rails and to the rear end of the said body. From Figures 1 and 2, it will be apparent that the side rails and back plate form a seat in conjunction with the body 1, which will serve to prevent the occupant of the coaster from falling off of the same.

Supported below the body 1 adjacent the rear end thereof, is a W-shaped metal frame 6, having arms 7, 8 and 9 respectively. Mounted transversely of the arms 7, 8 and 9, and held thereto by the cap bearings 10, is provided a rear axle 11, which extends through the side rails 3 and 4, and supports the rear wheels 12 and 13 on the ends of said axle. Mounted at the forward ends of the arms 7, 8 and 9 of the frame 6, and supported thereby by means of the cap bearings 14 I have provided a crank 15, on which the slidible collar 16 is mounted, which in turn supports the larger gear wheel 18 and the smaller gear wheel 11. The collar 16 may be suitably held on the crank 15 in any manner, but I have illustrated the same as being splined to the crank. The gear shift lever 19 is pivoted at point 20, and extends through the side rail 3, the upper portion of the lever being on the outside of the said rail 3, while the lower portion of the lever is positioned on the inside of the said rail, and is provided with a fork 21, which engages in a reduced slot 22 on the end of the collar 16. A suitable guide or retainer 23 is provided for the upper end of the gear shift lever 19 and is secured to the outside of the side rail 3, adjacent the top thereof, as clearly illustrated in Figures 1 and 2 of the drawings. The gear wheels 24 and 25 are fixed to the axle 11, and are adapted to be engaged by the gear wheels 17 and 18, respectively, depending upon the position which the gear shift lever is placed in. When the gear 17 engages the gear 24, it will be apparent that the gear train will be placed in position for operating the coaster on hilly ground, and when the gear wheel 18 is engaged with the gear wheel 55

25, the drive is in the proper position for operating the coaster on level ground.

Arranged adjacent the front end of the body 1, and extending therethrough, I have provided a pivoted drive or operating lever 26, the same being swivelly mounted at 27 to the body 1. A connecting rod 27' is connected between the crank 15 and through a ball and socket joint 28 to the lower end of the pivoted drive or operating lever, whereby when the operating lever is pulled backward and forced forwardly, the crank will be caused to rotate, thereby transmitting motion to the gears and to the rear axle and rear wheels. Suitable foot supports 29 will be supported on the lower end of the operating lever 26 and will extend outwardly therefrom in opposite directions, whereby the operator of the coaster may place his feet through the openings 2 and upon the foot supports 29.

20 Disposed upon the upper end of the operating lever 26 and supported thereby, is provided a collar 30 having laterally extending handle bars 31 formed at its upper end, and oppositely disposed or extending extensions 32 formed on its lower end.

30 Positioned at the forward end of the body 1, forwardly of the operating lever 26, I have provided a hollow L-shaped bracket 34, which extends through the body 1 and which is formed at its lower end with a hollow housing 35 in the lower wall of which is formed the arcuate slot 36. The front axle 37 supports the wheels 38 and 39 at its opposite ends and is supported upon a stub shaft 40, which is axially aligned with the hollow bracket 34. A slotted guide arm 41 is secured to the front axle 37 between the same and the lower surface of the hollow housing 35, the forward end of the slotted guide arm extending outwardly and lying immediately under the said arcuate slot 36 in the hollow housing 35. A vertically positioned steering shaft 42 extends through the hollow bracket 34, and is bent at right angles to extend through the hollow housing 35, and has its terminal end bent downward to extend parallel with the main portion of the said shaft. The 45 downwardly turned portion of the shaft extends through the slotted guide arm 41 and the arcuate slot 36 in the housing 35. The steering bar 43 comprising oppositely extending arms is secured at the upper end of the steering shaft 42 and has its ends connected with the ends of the opposite extensions 32, provision being made for adjustment by means of the flexible threaded links 44, whereby the steering wheels may be aligned, to track with the rear wheels 12 of the velocipede.

50 55 In Figure 6, I have illustrated a modification of steering mechanism in which the operating lever 30 is provided with the oppositely extending extensions 32 which are connected by the cable 44' passing about a pulley 43' on the steering shaft 42.

From the foregoing description it will be apparent that the mode of operation of my improved coaster is as follows:

The occupant will be seated on the body 1 and

will extend his legs through the leg slots 2 formed through the body, and place his feet on the foot bars or supports 29. By grasping the handle bars and pulling backwardly and pushing forwardly upon the same, motion will be transmitted to the connecting rod and the crank and gear train to the rear axle and wheels. When it is desired to steer the coaster to the right or left, it is only necessary to turn the handle bars to the right or left, the same being connected with the steering bar, will cause the wheels to turn in a corresponding direction.

From the foregoing description it will be apparent that I have devised a highly efficient and useful form of velocipede, and more particularly an occupant propelled coaster, which may be propelled jointly by the hands and feet, and steered by the hands.

Many minor changes in detail of construction may be resorted to without departing from the spirit of the invention.

Having thus described my invention what I claim as new and desire to secure by Letters Patent of the United States is:

1. In a vehicle of the class described, a body portion, front and rear wheels supporting the body portion, a hollow bracket secured to the body portion, a hollow housing formed integral with the lower end of the bracket, the bottom of the housing having an arcuate-shaped slot 30 formed therein, an axle for the front wheels, a depending stub shaft providing a king bolt, formed on the housing and extending through an opening in said axle, a slotted guide arm extending an appreciable distance forwardly from 35 said axle and having a slot extending inwardly from the free end thereof, a steering shaft disposed within the hollow bracket and having a forwardly extended portion disposed within the housing, the end of the forwardly extended end 40 portion operating within the slot of the housing and slot of the guide arm, and means for operating said steering shaft whereby the front wheels may be operated to guide the velocipede.

2. In a vehicle of the class described, a body portion, front and rear supporting wheels for the body portion, a hollow bracket secured to the body portion, a housing at the lower end of said bracket, said housing having an arcuate-shaped slot in the bottom thereof and disposed transversely of the housing, a guiding post within the hollow bracket, said post having a forwardly extended lower end portion disposed within the housing, the extremity of the forwardly extended portion being disposed downwardly through the slot in the housing, an axle for the front wheels pivoted to the hollow bracket, a guide arm secured to the axle and having a slot, the downwardly extended extremity of said guiding post operating within the slot of the guide arm, and adapted to transmit movement of the guiding post to the front axle, and wheels guiding the vehicle when the guiding post is operated.

IRA S. LEGGITT.
